WINDOW SASH LOCK

William B. Lang, West Palm Beach, Fla.

Application October 8, 1935, Serial No. 44,100

4 Claims. (Cl. 292—112)

This invention relates to a window sash lock and is designed primarily for use in connection with the sashes of casement windows, but it is to be understood that a sash lock, in accordance with this invention, is to be employed in any connection for which it may be found applicable, and the invention has for its object to provide, in a manner as hereinafter set forth, a lock of the class referred to for locking the upper end of a casement sash to provide a safeguard against storms and theft.

A further object of the invention is to provide, in a manner as hereinafter set forth, a lock of the class referred to capable of being installed relative to a casement window sash independent of and without interfering in any manner with the means generally employed at the bottom of a casement window for opening, closing and locking the latter.

Further objects of the invention are to provide, in a manner as hereinafter set forth, a window sash lock which is simple in its construction and arrangement, strong, durable, compact, readily installed relative to a window, thoroughly efficient in its use, conveniently operated to lock or release the sash, and inexpensive to manufacture.

With the foregoing and other objects which may hereinafter appear the invention consists of the novel construction, combination and arrangement of parts as will be more specifically referred to and as are illustrated in the accompanying drawings wherein are shown embodiments of the invention, but it is to be understood that changes, variations and modifications may be resorted to which fall within the scope of the invention as claimed.

In the drawings:

Figure 1 is a fragmentive view in vertical section of a casement window of the single sash type showing the adaptation therewith of the lock in accordance with this invention.

Figure 2 is a fragmentive view in rear elevation of a casement window of the single sash type showing the adaptation therewith of the lock in accordance with this invention.

Figure 3 is a sectional plan of a casement window of the single sash type showing the adaptation therewith of the lock in accordance with this invention.

Figure 4 is a fragmentive view in rear elevation of a casement window of the double sash type showing the adaptation therewith of a modified form of lock in accordance with this invention, and

Figure 5 is a detail in elevation of the operating mechanism for the lock.

Referring to Figures 1, 2 and 3 of the drawings, 1 and 2 indicate respectively the frame and sash of a casement window.

The lock includes a keeper 3 formed of a vertical leg 4 and a horizontal leg 5. The legs are disposed at right angles to each other and the lower end of leg 4 merges into the forward end of leg 5. The leg 4 is secured to the inner face of one of the side stiles 6 of the sash 2 in close proximity to the top stile 7 of the sash. The leg 4 is provided with spaced openings 8 through which extend holdfast devices 9 for anchoring the leg 4 against the stile 6. The leg 5 extends rearwardly from stile 6 and is formed with a lengthwise extending rectangular slot 10. The holdfast devices 9 are countersunk in the openings 8.

The lock includes a combined guide and coupling element 11 consisting of a yoke 12 having thick sides 13 formed with openings 14. The element 11 is positioned against a side 15 of the frame 1. The element 11 is disposed at an inclination with respect to said side 15. The element 11 extends at an inward inclination from its lower to its upper end and is arranged above the keeper 3. Holdfast devices 16 extend through the openings 14 for anchoring the element 11 to the side 15 of the frame 1. The body of element 11 is formed with a slot 17 extending lengthwise thereof. The length of the slot 17 is such as to extend from one of the sides 13 to the other. The slot is formed of an angularly disposed lower portion 18 and a vertically disposed upper portion 19. The portion 18 extends at a greater inward inclination than that of the element 11.

The lock includes a bolt member 20 formed of an elongated shank-part 21, a stem-part 22 and a hook-part 23. The bill of the hook is indicated at 24. One end of the stem-part 22 merges into the inner end of the hook-part 23. The other end of the stem-part 22 merges into one end of the shank-part 21. The stem-part 22 is vertically disposed. The shank-part 21 is disposed obliquely to the stem-part 22. The inner side edge 25 of bill 24 is beveled at its outer end, as at 26. Fixedly secured to the hook 23 is a coupling pin 27 which extends through the slot 17 and is upset, as at 28, to provide for slidably coupling the member 20 to the element 11. The member 20 is slidable relative to the element 11.

The lock includes an operating mechanism 29 consisting of a vertically disposed rectangular plate 29 provided with openings 30 for the passage of holdfast devices 31 for anchoring member 55

28 to the side 15 of the frame a substantial distance below the keeper 3. The plate 29 carries a shaft 32 for a segmental gear 33 and is formed with an offset part 33a against which the gear 33 rides. The plate 29, in proximity to its lower end, is formed with a pair of apertured spaced parallel ears 34 for rotatable shaft 35 having a worm 36 and a reduced squared end portion 37 upon which is secured, in laterally extended relation, a 5 socket forming member 37a for detachably receiving a crank handle 38 employed for rotating the shaft 35 whereby the worm 36 meshing with gear 33 will shift the latter. The plate 29, near its lower end, is formed with a slot 38a to provide 10 a clearance for the worm 36 to extend in whereby the gear 33 will seat against the offset part 33a. The lower end of the shank 21 is pivotally connected, as at 39, to the gear 33. The arrangement is such that when shaft 35 is rotated in one 15 direction, the bolt member 20 will be elevated and when shaft 35 is rotated in the opposite direction, the bolt member will be lowered.

The bolt member 20 is adapted to extend into the slot 10 of the keeper 3 to prevent the opening 20 of the sash 2 and also to engage the keeper 3 for the purpose of providing a snug closing fit for the sash 2 relative to the frame. The element 11 coacts with the pin 26 for guiding the bolt member 20 during its upward and downward movement and also for swinging the bill 24 clear of the keeper 3, as well as for moving the bill 24 against an end wall of the slot 10 for the purpose of drawing the sash 2 in to make a snug fit relative to the frame. The sash 2 is hinged to the frame as 25 at 40.

With reference to Figure 4, which shows a modified form of lock, a casement window is illustrated which includes a frame 41 and a pair of sashes 42, 43 which are suitably hinged to frame 40 41 and when in closed position, overlap. The front of the sash 43 overlaps the front of the sash 42 as indicated in dotted lines, Figure 4. Secured to the lower face of the top member 43 of the frame 41 is a combined guide and coupling element 44 of the same construction as the element 11. Secured to the top stile 45 of the sash 43 is a keeper element 46 of the same construction as the element 3. Slidably connected to the element 44 by the pin 47 is a bolt member 48 of the same 45 construction as the element 20, with this exception, that that end of the member 48 which is not provided with a hook is torsionally twisted, as at 49. Secured to the inner face of the side 50 of the frame 41 is an operating mechanism 51 which is 50 of the same construction as the operating mechanism 28. Pivotedly connected to the segmental gear 52 of the mechanism 51, as at 53, is an actuating bar 54 having its upper end torsionally twisted, as at 55.

60 Secured to the inner face of the side 50 of the frame 41 is a bracket 55 to which is pivotally connected, as at 56, a bell crank 57 having its arm 58 pivotally connected, as at 59, to the end 49 of member 48 and which has its other arm 60 pivotally connected, as at 61, to the end portion 55 of actuating bar 54. The member 48 operates relatively to the element 46 in the same manner as the member 20 operates with respect to the element 3.

70 The bolt member moves lengthwise with respect to the frame member 15 or frame member 42 and also transversely in opposite directions with respect to the member 15 or 42 and this movement

is accomplished by the operating mechanism in connection with the slot 19 in the element 11. When the bolt member interengages with the keeper element and with the bill of a bolt member arranged at the rear end wall of the slot in the keeper element, the sash or pair of sashes are locked from movement and with the locking arranged at the upper portion of such sash or sashes.

What I claim is:

1. In a window sash lock of that type including a keeper carried by a sash, the combination of a stationary combined guide and coupling element formed with an angle shaped slot, a shiftable bolt member having a part at one end adapted to extend into the keeper for locking the sash, means for slidably connecting that end of the bolt member provided with said part to said guide and coupling element to provide for the said end of the bolt member shifting in opposite directions relative to the keeper, and an operable means adapted to be secured to the window frame and pivotally connected with the other end of said bolt member for shifting said part into and out of the keeper.

2. In a window sash lock of that type including a keeper adapted to be carried by the sash, the combination of a manually operated shaft provided with a worm, a segmental gear meshing with and operated from said worm, supporting means adapted to be secured to a window frame for the said shaft and gear, a hook shaped bolt member adapted to engage in the keeper for latching the sash, a combined guide and coupling element adapted to be secured to the window frame and having one end of the bolt member slidably connected thereto, said combined guide and coupling element having means for moving said bolt member in opposite directions relative to the keeper, and means for pivotally connecting the other end of said bolt member with said gear.

3. In a window sash lock a bolt member including a hook-part, a stem-part merging at one end into the inner end of the hook-part and an elongated shank-part merging at one end into the other end of and disposed obliquely to the said stem-part, a stationary inclined member formed with an angle-shaped slot and having one of its terminal portions opposing one face of said hook-part, means extended through said slot for slidably connecting said hook-part to said member, and a bolt member shifting means connected to the other end of the shank-part and coacting with the latter said slot and the said slidably connecting means for shifting the hook-part to and from locking position.

4. In a window sash lock, a locking bolt including a hook-part, a stem-part having one end thereof terminating in the inner end of the hook-part and an elongated shank-part merging at one end into the other end of the stem-part, a stationary member formed with an angle-shaped slot and having an end terminal portion thereof opposing one face of the hook-part, means extending through said slot for slidably connecting said hook-part to said member, a manually operated shaft provided with a worm, a segmental gear meshing with and operated from said worm, supporting means for said shaft and gear, and means for pivotally connecting the other end of said shank to said gear.

WILLIAM B. LANG.
